(57) **CLAIM**

I claim the ornamental design for an album to preserve baby teeth, as shown and described.

DESCRIPTION

FIG. 1 is a front view of an album to preserve baby teeth.

FIG. 2 is a back view thereof.

FIG. 3 is a left side view thereof.

FIG. 4 is a right side view thereof.

FIG. 5 is a plan view, with a bottom view being a mirror image thereof.

FIG. 6 is a front view with the cover opened thereof;

FIG. 7 is a back view with the cover opened thereof;

FIG. 8 is a left side view with the cover opened thereof;

FIG. 9 is a right side view with the cover opened thereof;

FIG. 10 is a plan view of the inside with the cover opened thereof; and

FIG. 11 is a bottom view of the outside with the cover opened thereof;

FIG. 12 is a sectional view along line 12—12 with the cover opened thereof;

FIG. 13 is a sectional view along line 13—13 with the cover opened thereof;

FIG. 14 is a plan view of the case to preserve baby teeth on the upper side of the inner face of the cover thereof; and,

FIG. 15 is a sectional view along lines C—D—E—F—G—H—I—J.
